UNITED STATES PATENT OFFICE.

HARRY RALPH RICARDO, OF LONDON, AND HENRY ANSTRUTHER HETHERINGTON, OF BYFLEET, SURREY, ENGLAND.

INTERNAL-COMBUSTION ENGINE.

1,133,402.

Specification of Letters Patent. Patented Mar. 30, 1915.

Application filed February 1, 1915. Serial No. 5,560.

To all whom it may concern:

Be it known that we, HARRY RALPH RICARDO and HENRY ANSTRUTHER HETHERINGTON, subjects of the King of England, and residing, respectively, at London, in England, and Byfleet, Surrey, in England, have invented a certain new and useful Improvement in Internal-Combustion Engines, of which the following is a specification.

This invention relates to internal combustion engines operating on the two-stroke cycle and more particularly those of the type which comprise two working cylinders disposed side by side with their inner ends in free communication.

The present improvements have for their object to combine means whereby the reciprocating parts are more satisfactorily balanced than heretofore with arrangements to enable the crank casing to be used more efficiently as a pump chamber for compressing the combustible mixture and introducing it into the working cylinders.

According to this invention a third cylinder of larger diameter is disposed opposite to the two working cylinders the ends of all three cylinders opening into a closed crank chamber. The pistons of these three cylinders are so connected to a common crank shaft that the piston in the third cylinder is reciprocated oppositely to the pistons in the working cylinders the latter being substantially balanced by the third piston. All three pistons act as pumps and by their simultaneous outward movement first draw into the crank chamber the combustible mixture subsequently compressing it therein by their simultaneous inward motion.

In the preferred construction three separate crank pins are provided for the connecting rods of the three pistons, the crank pins for the pistons of the working cylinders being conveniently disposed on either side of a crank pin by which the third piston is reciprocated. The two crank pins of the working pistons are so relatively placed circumferentially about the shaft that one has a slight lead over the other.

The construction is such that in operation as all three pistons simultaneously move outward a partial vacuum is formed in the crank chamber until the inlet ports for the combustible mixture which are formed in or toward the end of one of the working

cylinders are uncovered. The combustible mixture is then drawn in and by the simultaneous inward movement of all three pistons is compressed in the crank chamber until such time as the inlet ports formed in the length of the wall of one of the working cylinders are uncovered. The exhaust ports are formed in the length of the wall of the second working cylinder whose piston is connected to the crank pin having the slight lead. As a result of this lead these exhaust ports are opened slightly before the inlet ports in the first cylinder are uncovered. Thus the exhaust begins to escape from the working cylinders through the second cylinder before the first charge enters the first cylinder from the crank chamber, this charge finding its way from the crank chamber through one or more passages formed around the end of the first working cylinder.

In the accompanying drawings, Figure 1 is a vertical sectional elevation through an engine constructed in accordance with this invention the section being taken on the plane in which lie the axes of all three cylinders. Fig. 2 is a vertical section on the line 2—2 of Fig. 1.

Like letters indicate like parts throughout the drawings.

The twin working cylinders A and B are formed and arranged side by side as clearly shown in Fig. 1 with their axes parallel and their inner ends in free communication through the passage C. The ends of these cylinders open into a closed crank chamber D to which the cylinders are rigidly connected. On the side of the crank chamber opposite to the cylinders A and B is a third cylinder E whose diameter is larger than that of either of the cylinders A and B. The inner end of this cylinder E opens into the crank chamber. The crank shaft F has three crank pins F', F², F³. The pins F', F² are connected by connecting rods to trunk pistons A', B' respectively in the cylinders A and B. The crank pin F³ is connected by a connecting rod to a piston E' in the cylinder E. The crank pin F² has a slight lead with respect to the crank pin F' as shown in Fig. 2. In the engine illustrated in the accompanying drawings by way of example the crank pin F³ is oppositely situated with respect to the crank pins F', F² so that the angle between the crank pin F³ and each of

the crank pins F' and F^2 is the same and almost 180° being short of this amount by one half the amount of lead that the crank pin F^2 has over the crank pin F' . In the 5 example illustrated this lead amounts to 20° so that the angle between the crank pin F^3 and each of the crank pins F' , F^2 is 170° .

In the wall of the cylinder A is formed a series of inlet ports G so disposed that they 10 are uncovered by the piston A' when it is near the end of its outward stroke. A corresponding series of exhaust ports H is formed in the wall of the cylinder B these ports also being so placed as to be uncovered 15 by the piston B' shortly before it completes its outstroke. The inlet ports G open into an annular chamber G' formed around the outer end of the cylinder A. The end of this chamber opens at G^2 into the crank chamber D. The exhaust ports H lead into a 20 annular chamber H' which communicates with the exhaust pipe H^2 . A second series of ports J is formed in the wall of the cylinder B beyond the exhaust ports H and in such a position that these ports J will be 25 uncovered by the piston B' just before it completed its instroke. The ports J open into an annular chamber J' which communicates at J^2 with the induction pipe from the carburetor. Owing to the proximity of the 30 annular exhaust chamber H' to the annular induction chamber J' the charge entering the latter is warmed by the exhaust products. A sparking plug is inserted in the 35 opening C' leading into the passage C between the ends of the cylinders A and B and the opening C^2 may conveniently be utilized for a compression tap.

In operation all three pistons simultaneously move away from the crank in so doing forming a partial vacuum in the crank case D. Just before the piston B' which has the lead completes its instroke the ports J are uncovered and combustible mixture is 40 forthwith drawn into the crank case. On the succeeding outstroke of all three pistons which takes place simultaneously this charge of combustible mixture is compressed until the piston A' has nearly completed its outstroke. The ports G are then 45 uncovered and the compressed charge at once enters the cylinder A passing to the inlet ports through the annular chamber G' . The charge sweeps through the passage C into the cylinder B driving before it the last 50 of the exhaust products from the preceding charge which are finding their way out of the cylinder B through the ports H which were uncovered just before the piston B' completed its outstroke. Owing to the lead 55 which the piston B' has over the piston A' the exhaust ports are uncovered in advance of the uncovering of the inlet ports G and consequently also the exhaust ports H are 60 covered on the succeeding instroke of the 65

piston B' slightly before the inlet port G are covered on the instroke of the piston A'. The instroke of all three pistons takes place simultaneously and the charge is compressed in the working cylinders A, B and the communicating passage C. The cycle as described is now recommencing the fresh charge being drawn into the crank chamber by the partial vacuum that has been created, this charge being compressed in the 70 crank chamber after the main charge in the cylinders A and B has been fired and while the pistons A', B' are performing their outstroke.

The upper side of the piston E' is conveniently formed as a trough E^2 which serves to contain lubricating oil. The crank pins F' , F^2 approach this trough so closely that the lubricant in the trough will be thrown about the crank case sufficiently to lubricate 80 the parts of the engine. The outer end of the cylinder E is conveniently provided with an opening E^3 as the side of the piston which faces this end of the cylinder has no work to do. The opening may be closed 85 with a convenient light casing to exclude dust.

The balancing effect obtained by the third piston can be regulated when constructing 90 the engine by determining the dimensions of the third cylinder and its accompanying piston with reference to the combined weights of the working pistons.

In the engine shown in the accompanying 95 drawings and described above the axes of all three cylinders lie in one plane, this being the preferred arrangement. In some cases however, it may be desirable to arrange the relative positions of the cylinders 100 slightly differently. Thus for example 105 while the two working cylinders A and B may lie with their axes in one plane which plane also includes the axis of the crank shaft, the third cylinder E may be thrown slightly out of this plane to one side or the 110 other. The relative positions of the crank pins may also be varied for example to accord 115 with the relative positions in which the cylinders are disposed. The extent of the lead given to one of the working pistons 115 over the other may be modified or dispensed with as found desirable.

The engine as illustrated in the accompanying 120 drawings is air-cooled but may be constructed for water cooling. The details of construction of the engine may be varied generally to suit requirements. The engine as illustrated may be considered to constitute a unit and two or more of such units 125 may be combined on one and the same crank shaft. It is desirable that the crank chamber of each unit be separated from the crank chamber of another unit but in such cases the arrangement may be varied as found 125 convenient.

It has been proposed in an internal combustion engine to employ three cylinders of which two were disposed side by side and the third of larger diameter opposite to them, the pistons being connected to three cranks so arranged that a balancing effect was obtained. In that case however all three cylinders were working cylinders and operated on the four-stroke cycle and neither of the pistons acted as a pump in conjunction with the crank case as in the present invention.

What we claim as our invention and desire to secure by Letters Patent is:—

15 1. In an internal combustion engine operating on the two stroke cycle the combination of a closed crank chamber, two working cylinders mounted side by side on and each opening as to one end into the crank chamber,
20 and as to the other end closed except for a free communication between the two cylinders, a third cylinder open at both ends and mounted on the crank chamber oppositely with relation to the working cylinders, pistons in the working cylinders operatively connected to like cranks on a shaft in the
25 crank chamber, a piston in the third cylinder operatively connected to a crank oppositely disposed on the shaft with relation to
30 the other cranks, ports in the wall of one working cylinder for the admission of the combustible mixture thereto, ports in the wall of the other working cylinder for the passage thence of the exhaust products, and
35 ports through which combustible mixture can be drawn into the crank chamber as set forth.

2. In an internal combustion engine operating on the two-stroke cycle the combination of a closed crank chamber, two working cylinders mounted side by side on and each opening as to one end into the crank chamber and as to the other end closed except for a free communication between the two cylinders, a third cylinder open at both ends and mounted on the crank chamber oppositely with relation to the working cylinders, pistons in the working cylinders operatively connected to like cranks on a shaft in the crank chamber, a piston in the third cylinder operatively connected to a crank oppositely disposed on the shaft with relation to the other cranks, ports in the wall of one working cylinder communicating with the crank chamber, a series of ports in the wall of the other working cylinder communicating with the exhaust passage, and a second series of ports in the wall of this working cylinder toward its open end communicating with the fuel supply passage, all the ports in the two working cylinders being controlled by the pistons in these cylinders as set forth.

3. In an internal combustion engine operating on the two-stroke cycle the combi-

nation of a closed crank chamber, two working cylinders having similar diameters mounted side by side on and each opening as to one end into the crank chamber and as to the other closed except for a free communication between the two cylinders, a third cylinder of larger diameter than either of the working cylinders open at both ends and mounted on the crank chamber oppositely with relation to the working cylinders, pistons in the working cylinders operatively connected to like cranks on a shaft in the crank chamber, a piston in the third cylinder of such dimensions as to equal approximately the combined weights of the two working pistons this third piston being operatively connected to a crank oppositely disposed on the shaft with relation to the other cranks, ports in the wall of one working cylinder for the admission of the combustible mixture thereto, ports in the wall of the other working cylinder for the passage thence of the exhaust products, and ports through which combustible mixture can be drawn into the crank chamber as set forth. 90

4. In an internal combustion engine operating on the two-stroke cycle the combination of a closed crank chamber, a crank shaft, two working cylinders having similar diameters mounted side by side on and each 95 opening as to one end into the crank chamber and as to the other closed except for a free communication between the two cylinders, a third cylinder of larger diameter than either of the working cylinders open at 100 both ends and mounted on the crank chamber oppositely with relation to the working cylinders, all three cylinders being arranged with their axes in one plane which cuts the axis of the crank shaft, pistons in the working cylinders operatively connected to like cranks on the shaft in the crank chamber, a piston in the third cylinder of such dimensions as to equal approximately the combined weights of the two working pistons 105 this third piston being operatively connected to a crank oppositely disposed on the shaft with relation to the other cranks, ports in the wall of one working cylinder communicating with the crank chamber, a series of 110 ports in the wall of the other working cylinder communicating with the exhaust passage, and a second series of ports in the wall of this working cylinder toward its open end communicating with the fuel supply 115 passage, all the ports in the two working cylinders being controlled by the piston in these cylinders as set forth.

5. In an internal combustion engine operating on the two-stroke cycle the combination of a closed crank chamber, two working cylinders mounted side by side on and each opening as to one end into the crank chamber and as to the other end closed except for a free communication between the 130

- two cylinders, a third cylinder open at both ends and mounted on the crank chamber oppositely with relation to the working cylinders, pistons in the working cylinders operatively connected to like cranks on a shaft in the crank chamber, a piston in the third cylinder operatively connected to a crank oppositely disposed on the shaft with relation to the other cranks, ports in the wall of one working cylinder communicating with the crank chamber, an annular exhaust passage surrounding the wall of the other working cylinder, a series of ports in the wall of this working cylinder communicating with the annular exhaust passage, a second annular exhaust passage surrounding the wall of this cylinder toward its open end but adjacent to the first annular exhaust passage this second annular exhaust passage communicating with a source of fuel supply, and a second series of parts in the wall of this working cylinder communicating with the annular fuel supply passage, all the ports in the two working cylinders being controlled by the pistons in these cylinders as set forth.
6. In an internal combustion engine operating on the two-stroke cycle the combination of a closed crank chamber constituting a fuel pump chamber, a three throw crank shaft in this chamber two of the cranks being similarly placed on the shaft while the third is placed between them along the shaft and oppositely disposed with relation to them, two working cylinders mounted side by side on and each opening as to one end into the crank chamber and as to the other end closed except for a free communication between the two cylinders, a third cylinder open at both ends and mounted on the crank chamber oppositely with relation to the working cylinders, pistons in the working cylinders operatively connected to the like cranks on the crank shaft, a piston in the third cylinder operatively connected to the third intermediate crank on the shaft, all three pistons operating in conjunction with the crank chamber as pumps, ports in the wall of one working cylinder communicating with the crank chamber, a series of ports in the wall of the other working cylinder communicating with an exhaust passage, and a second series of ports in the wall of this working cylinder toward its open end communicating with a fuel supply passage and serving to admit fuel from this passage to the crank chamber, all the ports in the two working cylinders being controlled by the pistons in these cylinders as set forth.
5. In an internal combustion engine operating on the two-stroke cycle the combination of a closed crank chamber constituting a fuel pump chamber, a three throw crank shaft in this chamber two of the cranks being similarly placed on the shaft while the third is placed between them along the shaft and oppositely disposed with relation to them, two working cylinders mounted side by side on and each opening as to one end into the crank chamber and as to the other end closed except for a free communication between the two cylinders, a third cylinder open at both ends and mounted on the crank chamber oppositely with relation to the working cylinders, pistons in the working cylinders operatively connected to the like cranks on the crank shaft, a piston in the third cylinder operatively connected to the third intermediate crank on the shaft, all three pistons operating in conjunction with the crank chamber as pumps, ports in the wall of one working cylinder communicating with the crank chamber, a series of ports in the wall of the other working cylinder communicating with an exhaust passage, and a second series of ports in the wall of this working cylinder toward its open end communicating with a fuel supply passage and serving to admit fuel from this passage to the crank chamber, all the ports in the two working cylinders being controlled by the pistons in these cylinders as set forth.
6. In an internal combustion engine operating on the two-stroke cycle the combination of a closed crank chamber constituting a fuel pump chamber, a three throw crank shaft in this chamber two of the cranks being similarly placed on the shaft while the third is placed between them along the shaft and oppositely disposed with relation to them, two working cylinders mounted side by side on and each opening as to one end into the crank chamber and as to the other end closed except for a free communication between the two cylinders, a third cylinder open at both ends and mounted on the crank chamber oppositely with relation to the working cylinders, pistons in the working cylinders operatively connected to the like cranks on the crank shaft, a piston in the third cylinder operatively connected to the third intermediate crank on the shaft, all three pistons operating in conjunction with the crank chamber as pumps, ports in the wall of one working cylinder communicating with the crank chamber, a series of ports in the wall of the other working cylinder communicating with an exhaust passage, and a second series of ports in the wall of this working cylinder toward its open end communicating with a fuel supply passage and serving to admit fuel from this passage to the crank chamber, all the ports in the two working cylinders being controlled by the pistons in these cylinders as set forth.

In testimony whereof we have signed our names to this specification in the presence of two subscribing witnesses.
